Primary Examiner—Philip S. Hyder*Attorney, Agent, or Firm*—Herbert Dubno[57] **CLAIM**

The ornamental design for a footlocker, showing my new design.

DESCRIPTION

FIG. 1 is front elevational view of a footlocker and fittings therefore showing my new design;

FIG. 2 is a rear elevational view thereof;

FIG. 3 is a top plan view thereof;

FIG. 4 is a bottom plan view thereof;

FIG. 5 is a right side elevational view thereof, the left side being mirror symmetrical thereto;

FIG. 6 is an enlarged perspective view of one of the top corner fittings on the footlocker;

FIG. 7 is an enlarged perspective view of one of the bottom corner fittings on the footlocker;

FIG. 8 is an enlarged front elevational view of the lock on the footlocker;

FIG. 9 is an enlarged right side elevational view of the lock on the footlocker;

FIG. 10 is an enlarged top plan view of the lock on the footlocker;

FIG. 11 is an enlarged bottom plan view of the lock on the footlocker;

FIG. 12 is an enlarged front elevational view of one of the clasps on the footlocker;

FIG. 13 is an enlarged right side elevational view of one of the clasps on the footlocker;

FIG. 14 is an enlarged top plan view of one of the clasps on the footlocker; and,

FIG. 15 is an enlarged bottom plan view of one of the clasps on the footlocker.

The broken line portions of the drawing disclosure are for illustrative purposes only and form no part of the claimed design.
